WALTER PARKS, OF DENVER, COLORADO, ASSIGNOR TO VAPOR CAR HEATING COMPANY, INC., OF CHICAGO, ILLINOIS, A CORPORATION OF NEW YORK

STEAM TRAP

Application filed June 10, 1927. Serial No. 197,852.

This invention relates to improvements in the construction of steam traps or vapor regulators of the type employed for thermostatically reducing steam from a high pressure to atmospheric pressure; as for example in heating systems where the steam is supplied at a high pressure and reduced to atmospheric pressure in the radiators. In heating systems like those employed in railroad passenger cars, steam is supplied at a high pressure and reduced to substantially atmospheric pressure before it is delivered to the radiators or heating coils. The means for reducing the pressure is thermostatically controlled and is provided with a thermostatic responsive element that is located in the path of the exhaust steam of the radiator. When the temperature of the steam as it leaves the radiator falls below a predetermined minimum, a valve is opened between the radiator and high pressure line so as to admit high pressure steam to the radiator. When this valve is opened, flow of steam through the radiator will commence and as soon as the steam that escapes from the radiator exceeds a predetermined temperature, the valve is automatically closed.

It is evident that the smaller the variations that are permitted in the temperature of the escaping steam, the better the regulation will be and the higher the efficiency of the heating plant.

This invention briefly described consists of a valve that is designed so that it may be located in the passageway from the high pressure steam supply to the radiator. This valve has means for normally holding it in open position and means for moving it to closed position, which last mentioned means is controlled by the temperature of the steam as it escapes from the radiator. The valve is so arranged that it opens against the pressure in the high pressure line and therefore when it is seated, the pressure of steam tends to hold it in a closed position. This is a very important consideration in valves of this type for the reason that if the valves are so made that they close against the high pressure steam, there will be wire-drawing when the valve is

about to close. This wire-drawing has a tendency to destroy the valve seat and the packing and will very soon destroy the efficiency of the valve whereas if the valve opens against the pressure in the high pressure line 55 and seats with the pressure, the pressure of the high pressure steam will force it against its seat thereby assuring a complete cutoff and obviating all danger of wire-drawing.

In order to more clearly described my invention and its operation, together with its advantages, references will now be had to the accompanying drawings in which the preferred embodiments have been illustrated and in which:

Fig. 1 is a vertical sectional view showing my valve in assembled position.

Fig. 1—A is a section of the non-freezing drip or nozzle through which the steam finally escapes.

Fig. 2 is a section taken on line 2—2 Fig. 1 and shows the valve to a somewhat enlarged scale.

Fig. 3 is a section taken on line 3—3 Fig. 2.

Fig. 4 is a section taken on line 4—4 Fig. 2.

Fig. 5 is a section taken on line 5—5 Fig. 1.

Fig. 6 is a section taken on line 6—6 Fig. 1.

Fig. 7 is a section taken on line 7—7 Fig. 1 and

Fig. 8 is a section through a portion of the thermostatic element showing the same to a substantially full scale.

Numerical 1 designates what may be termed the body member of the valve. This has been shown as forming an elbow having an upwardly extending portion whose top has been designated as numeral 2 and a horizontal arm whose end has been designated as numeral 3. The upper end portion 2 contains the high pressure valve mechanism and has been provided with two chambers 4 and 5 which are separated by a partition 6. The partition wall 6 has an opening 7 that is concentric with chambers 4 and 5. This opening has an enlarged portion whereby a shoulder 8 is formed. The end nearest chamber 5 is provided with a threaded portion 9. A cylindrical valve bushing 10 extends through the opening 7 and has an annular flange 11 that rests against the shoulder 8. This bushing is

held in place by means of a hollow bushing holder 12. This holder has a threaded portion 13 that cooperates with the threads 9 and when it is in place, it forces the flange 11 against the seat 8 thereby holding bushing 10 securely in place. Bushing holder 12 is provided with two pair of diametrically opposed openings 14 which are covered by means of screens 15. The tip of the bushing holder is preferably made square as indicated with numeral 16 so that it can be readily engaged by means of a wrench when parts are assembled. A cap 17 is provided intermediate its ends with an outwardly extending shoulder 18 and has its open end threaded so as to form a threaded engagement at 19 with the open end of chamber 5. The outer end of chamber 4 has a threaded opening 19 which is closed by means of a plug 20. This plug has a central opening for the reception of the cylindrical stem 21 of the valve. The valve bushing 10 is provided with a seat 22 on the end that communicates with the interior of the bushing holder. The movable valve member has a circular cylindrical portion 23 that has an easy sliding fit with the cylindrical opening in the valve bushing 10. This cylindrical portion is substantially the same length as the valve bushing and has an extension 24 of small diameter that projects into the interior of the bushing holder. The reduced portion 24 has an annular shoulder 25 adjacent the end of the cylindrical part 23. This shoulder forms an abutment for a removable part that has been designated by numeral 26. This part has a recess in the end adjacent the shoulder 25 and within this recess is located a washer 27 which may be formed of leather, fibre or any other suitable material, which when it engages the valve seat 22, will form a good steam-tight seal. Part 26 is secured to the cylindrical part 24 by means of nuts 27. The stem 21 which extends through the interior of plug 20 is provided at its outer end with a head 28 that has two spaced fingers 29 which are perforated for the reception of a pivot pin 30 that projects through the space 31 between the fingers 32 of a pivoted lever which will be herein after more particularly described. The inner end of plug 20 is provided with a stuffing box whose cap has been designated by numeral 33 and may be provided at its outer end with an annular recess containing some fibrous material 34 which may be saturated with oil for the purpose of lubricating the stem 21. Cylindrical part 23 is provided with a plurality of depressions or grooves 35 through which steam may pass and from which it may flow into the radial openings 36 in the valve bushing. This arrangement is shown more clearly in Figure 3 which is a section taken through openings 36. When the parts are in the position shown in Figures 1 and 2, steam may pass from the high

pressure steam pipe 37 into the high pressure chamber 5 and thence through the screen 15 and openings 14; pass through the opening between valve seat 22 and the washer 27, thence through the grooves 35 and the openings 36 into low pressure chamber 4, from which it will flow through the low pressure pipe 38 into a radiator (not shown).

The body member 1 has two spaced upwardly extending flanges 39 and 40 between which is located the stem 41 of the supporting member having two spaced upwardly extending arms 42, Figure 5. The stem 41 is clamped between sides 39 and 40 by means of bolts 43. The upper ends of the arms 42 are provided with apertures for the reception of pivot pin 44. Pivoted on the pin 44 is a lever having three arms which have been designated by letters "A", "B" and "C". Arms A and B extend substantially in a straight line and arm C projects at right angles from a line joining the ends of arms A and B. The lower end of arm C has two spaced fingers 32 that embrace the pivot pin 30 and lie between fingers 29 on the head 28 that is secured to the valve stem 21. The free end of arm B is provided with a threaded opening in which is mounted an adjustable bolt 45 held in adjusted position by a lock nut 46. The lower end of bolt 45 is provided with a groove in which is secured washer 47 against which the upper end of spring 48 abuts. The lower end of this spring surrounds an upward lug 49. Spring 48 is under compression and tends to move the free end of lever B upwardly; this of course tends to move the arm C toward the right (Figure 1) thereby moving the valve member to open position. It is evident from the above description that unless some external force is applied that will overcome the action of the spring 48, the valve will remain in an open position thereby allowing steam to flow from high pressure pipe 37 to low pressure pipe 38 that connects with the radiator. It is evident that if the valve remained open constantly, there would be an unnecessarily large amount of steam flow through the radiator and consequently a great loss of heat. Attention is called to the fact that spring 48 is so located that it is constantly surrounded by air and therefore it will retain its temper and resiliency indefinitely, whereas, if it is located in the steam passage, its temper will be destroyed. I will now proceed to describe the thermostatic means which operates to close the valve whenever the temperature of the steam that has left the radiator increases beyond a predetermined value.

The end 3 of body member 1 is provided with a chamber 50 which is provided on one side with an opening 51 which is threaded for the reception of one end of pipe 52 which connects with an exhaust opening in

the radiator. The steam that flows from chamber 4 and through passage 38 will pass through the radiator and after it has passed through the radiator, it will flow through pipe 52 into chamber 50 which may therefore be designated as the exhaust chamber. The lower wall of chamber 50 is provided with an opening to which is threadedly connected a short piece of pipe designated by numeral 53. To the lower end of this pipe is threadedly connected the upper end 54 of a hollow casting 55. The lower portion of this casting has a cylindrical wall 56 which is provided at spaced intervals with pairs of outwardly extending lugs 57 between which are pivotally connected bolts 58. These bolts are provided with winged nuts 59 and with thick washers 60 whose upper surfaces 61 are cylindrically convex. A cover member 62 is provided with a plurality of pairs of outwardly projecting lugs 63 between which the bolts 58 may pass. The lower sides of these lugs have concave recesses which are adapted to receive the convex surfaces 61 of the washers 60. This cover may be forced against the lower edge of the cylindrical wall 56 by the action of the clamping bolts 58 and the winged nuts 59. The upper surface of cover 62 is provided with a groove 64 which contains a ring 65 of some suitable gasket material. When the cover 62 is clamped against the open edge of the cylindrical end 56, a tight chamber is formed. This chamber has been designated by numeral 66 and will be referred to hereafter as the diaphragm chamber. Cover 62 is provided with a circular threaded opening 67 which is cooperatively associated with an adjusting screw 68. Secured to the upper end of the adjusting screw is a circular seat 69 which is provided with an upwardly extending flange 70 and is also provided with a plurality of openings 71. Supported on this seat is a thermostatic element which has been designated in its entirety by reference number 72. This element consists of a section of accordian pleated metal tubing 73 of the kind known to the trade as sylphon tubing. The lower end of this tubing is soldered to the outwardly extending flange 74 of a pressed metal member which has an upwardly extending conical side 75 that extends between the flange 74 and the bottom 76. The member formed by parts 74, 75 and 76 has the appearance of an inverted pan whose bottom is represented by numeral 76 and whose top has the outwardly extending flange 74. A circular plate 77 which is slightly upwardly convex has its outer edges soldered to the sylphon at 78. This assembly forms a thermostatic element having a hermetically sealed chamber which is normally full of air. Plate 77 is provided with an upwardly extending lug 79 which is provided with an opening 80. Secured to the under

side of the flange 75 is an annular ring 81. If opening 80 is sealed so that air cannot escape, it is evident that the air contained within the thermostatic element will increase in volume when the temperature increases; the expansion of the air will raise the convex plate 77 and thereby increase the distance from the bottom to the top of this element. As this element in actual construction has an outside diameter of over 4½ inches, it is evident that the expansion of the air will exert considerable force and this force is taken advantage of for the purpose of closing the high pressure steam valve.

Referring now more particularly to Figure 1, it will be observed that a rod 82 has the upper end connected with the free end of the lever arm A by means of a pivot pin 83. This rod extends through an opening 84 in the upper end of the exhaust chamber 50 and passes downwardly through the interior of pipe 53. The lower end of rod 82 rests on the upper surface of a cup 85 whose bottom is slightly concave so as to fit the upper convex surface of plate 77. A pin 86 extends upwardly from the center of the cup 85 and projects into an opening in the lower end of rod 82. When the thermostatic element is collapsed, spring 48 will operate to keep the high pressure steam valve in open position in the manner above explained.

Let us now assume that pipe 37 is connected to a source of high pressure steam and that the parts are in the position shown in Figure 1. This steam after passing through the radiator will finally enter exhaust chamber 50 and flow downwardly through pipe 53 into the diaphragm chamber 66 and after passing around the thermostatic element 72 will flow outwardly through the exhaust pipe 87 whose upper end is threadedly connected with sides of an opening 88 in the cover 62. As the temperature of the thermostatic element increases, due to the increasing temperature of the steam, the air enclosed within this element will begin to expand and as it expands, it moves the plate 77 upwardly thereby forcing the rod 82 to move upwardly and to rotate levers A, B and C in a clockwise direction against the tension of spring 48. This movement of the parts will cause the valve to move toward the seat 22 and when the temperature surrounding the thermostatic element has attained the prepredetermined heat, for example 203 degrees Fahrenheit, the high pressure valve will close thereby preventing the further flow of steam through the radiator. As soon as the high pressure steam ceases to flow, the steam within the radiator and the pipes 38 and 52 will continue to expand and reduce the temperature. When the steam reaches the diaphragm chamber 66, and the temperature has been reduced to 201 degrees Fahrenheit, the thermostatic element will be collapsed to

such an extent that spring 48 will function to again open the valve between the high pressure line and the radiator. The flow of live steam will soon increase the temperature until the valve closes and we will therefore have a continuous opening and closing action which will keep the temperature of the radiator and of the escaping steam constant within a very narrow limit. In order to protect the thermostatic element from being directly impinged upon by means of exhaust steam, I have provided a deflector 89 of conical shape whose vertex is provided with a cylindrical extension 90 that surrounds the rod 82 and which may be secured to the latter by solder or any other suitable way. The lower end of the deflector is of such diameter that it extends outwardly beyond the thermostatic element and also beyond the outside of the upwardly extending flange 70. A flexible hose connection 901 extends from the lower end of pipe 87 to the upper end of nozzle or drip 91. This nozzle has an outwardly flaring portion 92 that is suspended a short distance from the rail on which the car moves. The steam within pipes 87 and 901 forms a seal which protects the interior of the diaphragm chamber 66 from the external temperature. In order to further protect the diaphragm chamber from the disturbing influences of the surrounding atmosphere, I have enclosed the same in a housing consisting of a conical top portion 93 and a downwardly extending cylindrical wall 94. The parts 93 and 94 form a portion which may be termed a wind shield whose function it is to prevent the strong currents of air striking the exterior of the diaphragm chamber. The adjusting screw 68 is provided at a lower end with a slot 95 through which a sealing element may be extended. The object is to seal this adjusting screw after the parts have been adjusted so it cannot be tampered with by any unauthorized person.

In the manufacture of thermostatic element 72, this element is subjected to a predetermined temperature while the opening 80 in the lug 79 is still unsealed. This permits the air within the element to become heated to this temperature without expanding the element. When this temperature has been attained, the opening 80 is sealed. This is accomplished by inserting a screw 96 within the opening 80 and then covering the head of the screw with solder, which has been represented by 97. When the thermostat is properly adjusted and sealed, it will be exceedingly responsive to temperature changes and I have found that the high pressure valve will be opened and closed on a temperature variation of less than two degrees Fahrenheit. Since the thermostatic element was heated to a considerable degree before it was sealed, it is evident that when the temperature falls below that at which it was sealed, that the

pressure within the element will fall below atmospheric pressure and therefore at such low temperature, the element will have a tendency to collapse. When the temperature is low, however, the top cover member 77 rests upon the outer edge of the bottom 76 where this connects with sides 75 in the manner shown in Fig. 8. This prevents the high pressure valve from becoming unduly opened and also reduces the variation in the length of the thermostatic element so as to prevent the sides from being subjected to unnecessary strains which would be the case if they were permitted to become fully collapsed.

I have called attention to the diaphragm deflector 89 which protects the thermostatic element from the incoming vapor and the water of condensation with which this is accompanied. This is quite important because it keeps the thermostatic element dry and therefore it is in condition to quickly respond to temperature changes, whereas if it were permitted to become covered with water of condensation, the evaporation of this water would have a tendency to cool the element and thereby retard its operation.

Although I have not shown the radiator as connected to the device, I have explained that the pipe 38 extends to the radiator and that another pipe 52 extends from the exhaust in the radiator to the exhaust chamber 50. For the purpose of this description, pipe 38 represents the radiator and I want it distinctly understood that the amount of radiation surface is immaterial as far as this invention is concerned. It is therefore possible to connect opening 51 with the opening in the low pressure chamber by means of a short piece of pipe which has a very small radiating surface but which merely serves to conduct the steam or water of condensation from chamber 4 to chamber 50. When the radiator has been reduced to a short section of pipe as explained, my device will function admirably as a steam trap in which the water of condensation enters through pipe 37 and flows from chamber 5 to chamber 4 and then through a short circuiting pipe into the exhaust chamber 50 from which it passes outwardly through pipe 53 and through the diaphragm chamber 66. The parts can be so adjusted that as soon as the water passes through chamber 66, the valve between chamber 5 and 4 will automatically open but as soon as the water has been drained and live steam begins to flow, the temperature of this steam will cause the valve to close. With this arrangement, my device as above explained can be employed as a steam trap which will permit the water to escape and at the same time will prevent the loss of any appreciable amount of steam.

From the above, it will be apparent that I have produced a very simple control device by means of which the temperature of a ra-

diator may be maintained approximately constant at all times and in which the high pressure valve will be positively seated against the valve seat and will be acted upon by the high pressure steam to keep it from opening. The fact that the valve seats with the pressure instead of against it prevents wire-drawing and therefore makes it possible to maintain the valve seat in serviceable condition for a much longer period than would be possible if the valve closed against the pressure.

I also want to call particular attention to the construction of the thermostatic element which contains air instead of a volatile fluid such as is ordinarily employed for this purpose. By making this element of considerable diameter, it is possible to obtain as great a force as is necessary for the purpose of opening the high pressure valve and since air is very susceptible to temperature changes, the thermostatic element will control the operation of the high pressure valve within a very small limit of temperature variation.

Having described my invention, what I claim as new is:

1. A regulator for controlling the flow of steam comprising in combination, a body member provided with two chambers, one of which is adapted to be connected with the source of steam and the other of which is adapted to be connected to a radiator, said chambers being separated by a partition having an opening, a movable valve member extending through said opening, said valve member having an enlarged head located within the chamber that is connected with the source of steam whereby when the valve member is moved to closing position, it moves towards the chamber connected with the radiator, the other end of the valve stem extending through the other wall of the low pressure chamber, means comprising a lever and a spring for normally holding the valve in open position and thermostatic means for moving the valve towards closed position against the tension of the spring whenever the thermostatic means is subjected to a temperature above a predetermined value.

2. A device for controlling the flow of steam from a high pressure supply to a radiator operating at a lower pressure, comprising a body member having a chamber in communication with the high pressure supply, another chamber in communication with the radiator, a partition separating said chambers, said partition having an opening, a movable valve member in said opening, said member having an enlarged portion within the high pressure chamber, and a stem extending through the low pressure chamber, to the outside thereof, means comprising a spring and lever for exerting a force tending to move the valve member farther into the high pressure chamber, means comprising a

thermostatic element for moving the valve member towards closing position, and a shield enclosing the thermostat.

3. A device for controlling the flow of steam comprising, in combination a body member having three separate chambers, two of which are adjacent to each other and separated by a partition, said partition having an opening controlled by a valve, said valve comprising a movable member extending entirely through one chamber and into the other, the last named chamber being adapted to be connected with a source of high pressure steam supply, means comprising a spring and a lever for holding the valve in open position, a thermostatic device located in a passageway from the third chamber, means for connecting the thermostat to the valve so that the valve will be opened and closed in accordance with temperature conditions and means for shielding the thermostat against extraneous temperature variations.

4. A device for controlling the flow of steam to a radiator comprising, in combination, a body member having two chambers separated by a partition, one of said chambers being a high pressure chamber adapted to be connected with a source of steam under pressure and the other being a low pressure chamber adapted to be connected with the interior of a radiator, the partition having an opening provided with a valve seat in the end that terminates in the high pressure chamber, the opposite wall of the low pressure chamber having an opening in axial alignment with the opening in the partition, a valve stem extending through the low pressure chamber and through the two openings, the end of the valve stem that extends into the high pressure chamber being provided with an enlarged head adapted to cooperate with the valve seat to prevent steam from flowing from the high pressure chamber into the low pressure chamber, means for forming a seal between the valve stem and the opening in the outer wall of the low pressure chamber, means comprising a spring for exerting a pressure on the valve tending to move it away from its seat and into the high pressure chamber, said body member having a third chamber adapted to be connected with the exhaust side of the radiator, a hollow member forming a thermostat chamber and having its interior connecting with the interior of the last mentioned chamber, a thermostat within the thermostat chamber, means connecting the valve with the thermostat so that the valve will be moved inwardly into the high pressure chamber when the temperature within the thermostat chamber decreases below a predetermined value and a shield enclosing the thermostat chamber.

5. A device for controlling the flow of steam to a radiator comprising, in combination, a body member having two chambers

separated by a partition, one of said chambers being a high pressure chamber adapted to be connected with a source of steam under pressure and the other being a low pressure chamber adapted to be connected with the interior of a radiator, the partition having an opening provided with a valve seat, the opposite wall of the low pressure chamber having an opening, a valve stem extending through this opening and guided in the partition opening, said stem having a valve within the high pressure chamber adapted to cooperate with the valve seat to control the flow of steam between the high and the low pressure chambers, means for forming a seal between the valve stem and the opening in the outer wall of the low pressure chamber, resilient means mounted outside the chambers and cooperating with the valve stem for normally holding the valve away from the seat, said body member having a third chamber adapted to be connected with the exhaust side of a radiator, a hollow member forming a thermostat chamber and having its interior in communication with the third chamber, a thermostat within the thermostat chamber, means connecting the thermostat with the valve so that the valve will move to open position when the temperature within the thermostat chamber decreases below a predetermined value, said thermostat chamber having an opening in communication with the atmosphere, said opening being formed by a tubular member (87) with which the escaping steam cooperates to form a seal.

6. A device for controlling the flow of steam to a radiator comprising, in combination, a body member having two chambers separated by a partition, one of said chambers being a high pressure chamber adapted to be connected with a source of steam under pressure and the other being a low pressure chamber adapted to be connected with the interior of a radiator, the partition having an opening provided with a valve seat, the opposite wall of the low pressure chamber having an opening, a valve stem extending through this opening and guided in the partition opening, said stem having a valve within the high pressure chamber adapted to cooperate with the valve seat to control the flow of steam between the high and the low pressure chambers, means for forming a seal between the valve stem and the opening in the outer wall of the low pressure chamber, resilient means for normally holding the valve away from the seat, said body member having a third chamber adapted to be connected with the exhaust side of a radiator, a hollow member forming a thermostat chamber and having its interior in communication with the third chamber, a thermostat within the thermostat chamber, means connecting the thermostat with the valve so that the valve will move to open position when the temperature within the thermostat chamber decreases below a predetermined

value, said thermostat chamber having an opening in communication with the atmosphere, said opening being formed by a tubular member (87) with which the escaping steam cooperates to form a seal and a shield enclosing the thermostat chamber.

7. A regulator for controlling the flow of steam comprising, in combination, a body member provided with two chambers, one of which is adapted to be connected with the source of steam and the other of which is adapted to be connected to a radiator, said chamber being separated by a partition having an opening, a movable valve member for controlling the flow of steam through the opening, said valve having a stem that extends through the wall of one of said chambers and is guided through the partition opening, a valve on the stem and located in the other chamber and adapted to close the valve opening, a spring located on the outside of the device, one end of the spring being connected with the body member and the other with the valve stem for exerting a force tending to move the valve to open position, and thermostatic means for moving the valve to closed position against the tension of the spring when the thermostatic means is subjected to a temperature above a predetermined value.

8. A steam regulator for a railway car heating system which includes a steam train pipe and a radiator, said steam regulator being provided with a high pressure chamber connected with the train pipe, a low pressure chamber connected with the radiator and a port between said chambers, and a thermostat chamber connected with the radiator, a valve in the high pressure chamber, a reciprocating valve operating rod extending into and through the low pressure chamber into the high pressure chamber, a thermostat element in the thermostat chamber, mechanism positioned outside the chamber for imparting movements to said valve operating rod comprising a bell crank, a rod extending from the thermostatic element for rocking the bellcrank and a spring which is stressed by the valve closing movements of the bellcrank.

9. A steam regulator for railway car heating system which includes a steam train pipe and a radiator, said steam regulator being provided with a high pressure chamber connected with the train pipe, a low pressure chamber connected with the radiator and a port between said chambers, a valve in the high pressure chamber, a reciprocating valve operating rod extending through the low pressure chamber into the high pressure chamber, mechanism for imparting movements to said valve operating rod comprising a bellcrank connected with said rod, a thermostatic element for rocking the bellcrank, and a spring located out of contact with the steam passing through the regulator

and normally tending to open the valve which is stressed by the valve closing movements of the bellcrank.

10. A steam regulator for a railway car heating system which includes a steam train pipe and a radiator, said steam regulator being provided with high and low pressure chambers communicating with said train pipe and radiator, respectively, a valve to control communication between said chambers, a 5 thermostatic member for operating said valve, a housing having an outlet for water of condensation which, except for said outlet, completely encloses the thermostat, and a drip pipe on the housing having a flexible section which extends close to the track.

In testimony whereof, I affix my signature.
